UNITED STATES PATENT OFFICE.

HEINRICH STOLL, JR., OF REUTLINGEN, GERMANY.

LAMB KNITTING-MACHINE.

No. 815,760.

Specification of Letters Patent.

Patented March 20, 1906.

Application filed January 8, 1903. Serial No. 138,289.

To all whom it may concern:

Be it known that I, HEINRICH STOLL, Jr., a citizen of the German Empire, residing at Reutlingen, in the Kingdom of Würtemberg, Empire of Germany, have invented certain new and useful Improvements in Lamb Knitting-Machines, of which the following is a description, reference being had to the accompanying drawings, and to the letters and figures of reference marked thereon.

The present invention relates to improvements upon the Lamb type of knitting-machines, especially that type in which goods embodying different-colored designs may be produced.

The special object of the present invention is to provide an improved auxiliary thread-guide working in connection with the lock, whereby it is possible on Lamb machines to dispense with the necessity of having a special pattern-plate for every pattern.

In the accompanying drawings, Figure 1 represents the lock on a Lamb knitting-machine. Fig. 2 is a similar view. Fig. 3 represents the invention as applied to a Lamb knitting-machine. Fig. 4 is a top plan view of Fig. 3. Figs. 5 and 6 are respectively front and plan views of the auxiliary thread-guide.

In the drawings, and referring to Figs. 1, 2, 3, and 4 particularly, which represent portions of a Lamb knitting-machine having a thread-guide 5, that is connected by a bracket 17 to a slide 15 under the control of a pattern-cam 13, the slide being provided with a suitable antifriction-roller 16, held in place against the cam by means of a tension - spring 14, the frame is provided with a suitable bracket having bearings for a pair of parallel shafts 9 and 12, the latter carrying the pattern-cam 13. On shaft 12 is secured a ratchet-wheel 11, with which engages a pawl 8, that is pivoted to a slide-bar 18, normally held in retracted position by a spring 19. On slide 18 is a cam-shaped block 20, with which engage cams 10, carried by the shaft 9, and at each ninety degree movement of the shaft the slide 18 is moved forward and the ratchet-wheel turned to the extent of a single tooth. This movement transmitted to the revolute cam moves the thread-guide to and fro, as dictated by the pattern and is commonly employed in machines of the Lamb type.

In the construction shown in Figs. 5 and 6

the thread-guide mechanism is supported by bracket-arms A and C, connected by a vertical arm B, and this arm C forms a support for a sliding block c, that carries the thread-guide b, said guide being moved to and fro to distribute the pattern-threads to the needles. The block c is secured to a longitudinally-movable bar a, mounted in guiding-openings in the bracket, and secured to one side of the bar are two racks E and F, having ratchet-teeth facing, respectively, in opposite directions. The bracket A is provided with bearings for the reception of three transversely-disposed parallel shafts d, e, and H, the latter shaft carrying disks or wheels h for the support of a cam or pattern chain m, having links or blocks l. The shaft e carries a bell-crank lever f, having two arms f' and f'', while shaft e carries a bell-crank lever g, having arms g' and g''. The arms f' and f'' are provided with cam-shaped ends for engagement by the pattern-chain m. The arms f'' and g'' carry pawls i and p, respectively, said pawls engaging the racks E and F and being held in operative position by means of suitable springs n, and the tails of the pawls are under the control of a double cam o, which places either pawl in inoperative position when it is retracted.

During the operation of the mechanism the pattern-chain, operated by the pawl-and-ratchet mechanism shown in Figs. 3 and 4, will act on one of the arms—arm g', for instance—and effect through the pawl k a movement of the thread-guide carrier-bar a to the right, the teeth of the rack F being of a pitch corresponding to that of the needles. When a full movement to the right is completed, the cam o will move said pawl k to inoperative position, and a corresponding movement of pawl i will then occur, the bar a being moved to the left.

Having thus described my invention, what I claim, and desire to secure by Letters Patent, is—

1. A thread-guide, a carrier-bar therefor, having oppositely-facing racks, pawls for engaging said racks, and a pattern-chain controlling the movement of the pawls.

2. In a Lamb knitting-machine the combination with a pattern-chain of a thread-guide-shifting bar arranged at right angles thereto with means for reciprocating the same in the direction of its length, compris-

ing bell-crank levers supported on suitable shafts, one arm of said bell-crank levers being adapted to engage the pattern-chain and the other arm having pawls adapted to engage the teeth on the sliding block, said teeth being arranged as shown, substantially as described.

In testimony whereof I affix my signature in presence of two witnesses.

HEINRICH STOLL, JUNIOR.
